CLAIM

The ornamental design for a main body of pump dispenser, as shown and described.

DESCRIPTION

FIG. 1 is a front, right side, top perspective view of a main body of pump dispenser showing our new design thereof; FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged-scale cross-sectional view thereof, taken in the direction of line 8-8 of FIG. 2;

FIG. 9 is an enlarged-scale cross-sectional view thereof, taken within and in the direction of line 9-9 of FIG. 2;

FIG. 10 is a side view thereof, shown in an exploded environment of use with an exemplary ring for pump dispenser;

FIG. 11 is a side view thereof, shown in an assembled environment of use with an exemplary ring for pump dispenser; and,

FIG. 12 is a partially enlarged bottom plan view thereof, taken within an area of arrows 12-12 of FIG. 7.

The evenly broken lines are shown for the purpose of illustrating environmental subject matter of an exemplary ring for pump dispenser that form no part of the claim. The dot-dash lines represent the designation of enlargement views as well as the designation of cross sectional views and form no part of the claim.
